CLAIM

The ornamental design for a battery cable assembly, as shown and described.

DESCRIPTION

FIG. 1 is a top left rear perspective view of a new design for a battery cable assembly comprised of battery clamps, battery cables, a fuse holder and a connector end; FIG. 2 is a top plan view of FIG. 1;

FIG. 3 is an enlarged top right rear perspective view of the battery clamps connecting to the battery cables of the battery cable assembly;

FIG. 4 is an enlarged top left rear perspective view of a connector end of a battery cable assembly;

FIG. 5 is an enlarged top left front perspective end view of a connector end of a battery cable assembly;

FIG. 6 is an enlarged top plan view of a connector end of a battery cable assembly;

FIG. 7 is an enlarged bottom plan view of a connector end of a battery cable assembly;

FIG. 8 is an enlarged left side elevational view of a connector end of a battery cable assembly;

FIG. 9 is an enlarged right side elevational view of a connector end of a battery cable assembly;

FIG. 10 is an enlarged front end view of a connector end of a battery cable assembly; and,

FIG. 11 is an enlarged opposite end view of a connector end of a battery cable assembly.
